ANTIFREEZE DEVICE

Alexander Merdan and Alexander J. Merdan, Jr.,
New York, N. Y.

Application July 24, 1947, Serial No. 763,196

6 Claims. (Cl. 219—38)

1

This invention relates to new and useful improvements in an anti-freeze device for automobiles, airplanes and other motor vehicles.

This application contains subject matter in common with the previously filed application, Ser. No. 731,174, filed February 27, 1947.

More specifically the present invention proposes the construction of a device for installation in a motor block or radiator. The device operates electrically by way of a resistance unit, and includes a movable part, this movable part preferably being a bodily movable one as a disc, piston or cylinder, which when in one position closes a circuit and in another position opens the same; so that as the temperature of the weather nears the freezing point the ice expansion causes the disc or the like to move away from its position which holds the circuit open to its other position, thus causing a contact to close the electric circuit, and causing the resistance unit to operate the device by causing it to operate the resistance unit at a sufficient heat. As the freezing point endangers the motor, with the motor's water jacket unprotected by being prepared with insufficient anti-freeze, or perhaps none at all, the device operates automatically to go on and off to protect the motor from cracking.

Still further, it is proposed to provide a device as aforesaid having an ice operated outlet valve for controlling the electric resistance heater.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of the device.

Fig. 2 is a side view of the device.

Fig. 3 is a top plan view of the device.

Fig. 4 is a section on the line 4—4 of Fig. 2.

Fig. 5 is an axial or diametric section of the device, on an enlarged scale, and showing the device in operative condition due to ice formation from water expansion after the water has come to a freezing temperature.

Fig. 6 is an exploded perspective view of certain parts shown in Fig. 5, these parts being included in the cylinder or piston which carries the resistance unit.

Fig. 7 is an exploded perspective view showing all the parts of the cylinder and also all parts of the resistance unit in the cylinder.

2

Fig. 8 is a bottom plan view on an enlarged scale of one of said parts, the same being a body of insulation carrying the resistance element.

Fig. 9 is a sectional view, on a further enlarged scale, taken on the line 9—9 of Fig. 8.

Fig. 10 is a view similar to Fig. 5, but showing the device in normal condition or when the temperature of the water is below the freezing point.

Fig. 11 is a bottom perspective view of the resistance unit.

The anti-freezing device according to this invention comprises a casing 10 having a threaded nipple 11 adapted to be screwed into the cooling system at any desired and appropriate place for allowing water in the water jacket of an engine to enter the nipple. The nipple is of large enough diameter to allow ice formed after the water has reached the freezing point, to enter the bottom open mouth of the nipple as indicated at 12 in Fig. 5.

Nipple 11 may be secured in the motor block by a suitable hole tapped in the block for the installation of the nipple, or the nipple may be more permanently mounted in the motor block in any suitable way, since the removal of the nipple is at no time necessary.

The casing is a cylindrical shell closed at its top by a cap 14. The shell 10 and the cap 14 are telescoped at their juncture, by means of a ring 15 permanently suitably attached around its upper portion to the lower portion of the cap. The ring 15, here shown as of one-piece construction with the cap 14, is received into the upper portion of the shell 10, for the telescoping joint, and then screws 16 are applied for removably locking the cap 14 on top of the shell 10 thereby to close the casing.

The cap 14 has suitably secured therein an even cylindrical side wall 16 which depends into the interior of the cap. Within the wall 16 is a cylindrical fitting 17, made of non-conductive material such as hard rubber or plastic. It has a central bore 22 through which passes a bolt 22' having a counter-sunk head 19. An insulation disc 20 is engaged over the cylindrical fitting 17 and when a nut 21 is applied to the upper threaded end of the bolt 22', the bolt may be tightened over a suitable electric lead.

A larger bore 22^a is formed below bore 22 in the cylindrical fitting 17 and is provided with a coil spring 22^b, adapted to contact the bolt head 19 at one end and the head 22^c of a plunger rod 22^d at the other end. The plunger 22^d passes through another communicating bore 22^e and permits free sliding motion for the plunger rod 22^d.

The bolt, spring and plunger rod are of some metal of high electrical conductivity, as the upper portion of the bolt is to form one post of an electric circuit, to which post will be secured a wire for conducting electric current.

The fitting 17 may be locked in place within the cylindrical wall 16 in any way desired but as here shown it is assumed to be permanently locked in place within said wall by a tight force fit.

The other wire of the circuit is secured to a post 23 which is here comprised of the threaded shank of a roundhead screw 23^a to which the other wire for conducting electric circuit may be attached under a nut 24. To prevent accidental loss of the screw 23^a on careless removal of the nut, the screw may be permanently attached at its head to the inside of the top or cap 14; for instance, by using a brass screw and brazing the head to the inside of the cap, which latter, as is also the shell 10, is desirably of brass.

Within the smooth cylindrical interior of the shell 10 is a cylinder or piston structure marked generally 25, which as shown in Fig. 6 when compared with Fig. 8, comprises a cup 26, topped by an apertured cover-disc 27, such cover-disc thus being in the form of a ring. The cylinder 26 carries contact 28 which is in engagement with the inner wall of the cup 26 and is held in position by the outer periphery of the cover disc 27. The cylinder 25 is normally in the bottom of the shell and is electrically grounded to the shell and cover-disc 27.

If the water in the water jacket of an engine freezes, the ice will cause it to expand and force the cylinder 25 upwardly until the contact 28 carried by the cylinder, and projected upwardly through the opening in the cover disc 27, contacts the plunger rod 22^d.

When this happens, a circuit is closed through a resistance unit within the cylinder; the circuit for energizing this unit including the wire going to the post provided by bolt 22^c, the spring 22^b and the plunger rod 22^d which connects with the contact 28, the screw 29 upwardly threaded into the lower part of said contact and connected to one end 31^a of the resistance element 31, the cover-disc 27 connected with the other end 31^b of the resistance element 31, the cup 26, the shell 10 and then the cap 14, to the post provided by screw 23^a, and so to the other wire of the circuit.

The cup 26 and the cover disc 27 are made of electrically conductive material, preferably brass. The fit between the outside surface of the cylindrical wall of cup 26, and the inner surface of casing 10, is such that while easy piston-like movement of the cylinder 26 up and down in the shell 10 is provided for, the fit is so close that water may not enter the shell 10 above the top of the cylinder cup 26. The bottom edge of cylinder 14 and the top edge of cylinder 26 form a water-tight contact when the cylinder 26 is expanded and prevents the water from getting into the cylinders.

The cover disc 27 is secured in place in the top of the cylinder 26 in any suitable way, as by brazing.

The structure provided inside the cylinder 26 for having the latter carry the resistance heating unit 31, and to prevent any possible chance of short circuiting the resistance unit, is most clearly shown in Fig. 7, when compared with Figs. 9 and 10.

In the bottom of the cylinder cup 26 is a stack of sheets or a block of mica 30 of disc-like shape,

with its circumference closely approaching that of the interior circumference of the cup 26. The mica element 30 is provided with a series of apertures 32 spaced around the same, which is used as an insulation against the heat of the resistance unit 31 to the brass cup 26 and so to the ice 12.

Immediately above the mica element is a body 33 of insulating material for carrying the resistance unit. The body 33 is in the shape of a short cylinder having in its bottom an annular groove 34. The resistance unit incorporates a coil of high resistance wire such as nichrome, and such coil is housed in the groove 34.

The body 33 is formed of a suitable ceramic material, as porcelain, and as formed to establish the groove 34, includes inner and outer depending skirts respectively marked 35 and 36, with the groove 34 surrounding the skirt 35 and being surrounded by the skirt 36.

Between the top and bottom of the body 33, the outer skirt 36 is provided with a series of radially directed apertures 37, these apertures spaced around the skirt, for more ready transfer of heat from the resistance unit 33 to the cylinder cup 26 and so to the ice 12.

The contact 28 is carried at the top of the body 33, said contact being a disc of less diameter than the central opening in the cover-disc 27. This cover-disc is immediately above the body 33, and is secured to the cup 26, as by brazings as already explained.

The contact 28, which then projects above the top limit of the cover-disc 27, is the head of a stud 38, made of a conductive material, as metal. The inner skirt 35 of the insulating body 33 surrounds a recess 39, and the shank of the stud is received in a central aperture in the body 33 communicating with the roof of said recess. The lower end of the stud shank which is hollow and internally threaded, is of reduced diameter, as shown at 40, which in turn contacts wire lead.

This portion 40 of the stud is provided with a pair of aligned apertures 41 extending to the interior of the stud portion 40 a slight distance above the upper end of the thread therein. The top of the thread carrying recess in the stud portion 40 is made flat, as the result of a suitable machining operation after said recess is drilled out before being tapped.

The screw 29 of brass or the like, and threaded to take the thread in the stud portion 40, has the free end of its shank rounded for safe yet secure clamping of an intercepted portion of the end extension 31^a from the resistance unit 31, against the flat upper end of the threaded recess in the stud portion 40, when the screw is fully tightened up. This end extension 31^a of the resistance unit 31 goes through an aperture 43 in the inner skirt 35 of the insulating body 33 and then through the aligned apertures 41 in the stud portion 40.

The other end extension 31^b of the resistance unit 31 passes through an aperture 45 extending upward from the groove 34 to the top of the insulating body 33 and thence to an aperture 46 through the cover-disc 27, where the same is soldered thereto.

Inside the casing made up of the shell 10 and the cap 14, is an expansive cylindrical coil spring 47, at its top centered about the cylindrical wall 16 and at its bottom resting on the top of cylinder 25 well out of the way of contact 28.

The apertures 18 and 18' are breather holes to facilitate easy up and down movement of cylinder 26.

der 25. The apertures 18, which it will be noted, are larger than the apertures 13, have a further useful function. They may also act as orifices for spill there-through of water when the same, due to expansion consequent upon first formation of ice crystals, causes an initial slight rise of cylinder 25. As is well known, water crystals form first on the surface of the water, and the spill just referred to tends to cause a movement of the water toward the apertures 18, which in turn results in causing the ice formation to build vertically upward in and above nipple 11, thereby strongly to thrust the cylinder 26 to a height where contact 28 touches plunger rod 22^d at the bottom of insulated fitting 17.

The operation of the device is as follows:

When the temperature of the weather nears the freezing point, the water in nipple 11 freezes and forms ice which expands against the bottom of cylinder 25, raising the cylinder until the contact 28 touches the plunger rod 22^d at the top of the device. This contact closes the circuit between the wires connected to the plunger rod 22^d and 23, and electric current flows through the resistance heating unit.

After the device has been raised in temperature again, the ice in nipple 11 will begin to melt, and the pressure from the ice on the bottom of cylinder 25 will be relieved, and so free the spring 46 again to expand, thus forcing the cylinder 25 down in shell 10. This will break the circuit by separating contact 28 from plunger rod 22^d, whereupon the resistance unit cools. Thus the circuit will be automatically made and broken to keep the water from freezing to a dangerous state.

While we have illustrated and described the preferred embodiments of our invention, it is to be understood that we do not limit ourselves to the precise constructions herein disclosed and the right is reserved to all changes and modifications coming within the scope of the invention as defined in the appended claims.

Having thus described our invention, what we claim as new and desire to secure by United States Letters Patent is:

1. An anti-freeze device for preventing the freezing of water in a cooling system, comprising a casing, a nipple at its lower end opening into the lower portion of the casing, said nipple being connected to the cooling system, a piston normally resting on the lower portion of the casing and in position to receive upward pressure from ice rising in the nipple whereby the piston is caused to rise in the casing by upward pressure of the ice, a resistance unit mounted on said piston, the casing and the piston being of electrically conductive material whereby regardless of the position of the piston in the casing mutually touching parts of the piston and the casing act together to form a conducting means for electricity, one end of the resistance unit being connected to the piston, means mounted on the piston for otherwise electrically insulating the resistance unit from the piston, a contact projecting from the top of the piston and connected to the other end of the resistance unit, a contact inside the casing carried thereby but insulated therefrom, a coil spring inside the casing above the piston for normally holding the piston in the lower portion of the casing to disengage said contacts, said contacts being so spaced in the direction of rise of the piston that when the piston is forced upward against said spring by ice rising in said nipple said contacts engage to connect the resistance with a source of electrical energy.

2. An anti-freeze device for preventing the freezing of water in a cooling system, comprising a casing, a nipple at its lower end opening into the lower portion of the casing, said nipple being connected to the cooling system, a piston normally resting on the lower portion of the casing and in position to receive upward pressure from ice rising in the nipple whereby the piston is caused to rise in the casing by upward pressure of the ice, a resistance unit mounted on said piston, the casing and the piston being of electrically conductive material whereby regardless of the position of the piston in the casing mutually touching parts of the piston and the casing act together to form a conducting means for electricity, one end of the resistance unit being connected to the piston, means mounted on the piston for otherwise electrically insulating the resistance unit from the piston, a contact projecting from the top of the piston and connected to the other end of the resistance unit, a contact inside the casing carried thereby but insulated therefrom, a coil spring inside the casing above the piston for normally holding the piston in the lower portion of the casing to disengage said contacts, said contacts being so spaced in the direction of rise of the piston that when the cylinder is forced upward against said spring by ice rising in said nipple said contacts engage to connect the resistance with a source of electrical energy, the resistance unit in the cylinder being insulated from the latter by means including a body of mica in the bottom of the piston, said mica body having a plurality of spaced apertures leading to said cylinder bottom for facilitating transmission of heat thereto.

3. An anti-freeze device for preventing the freezing of water in a cooling system, comprising a casing, a nipple at its lower end opening into the lower portion of the casing, said nipple being connected to the cooling system, a piston normally resting on the lower portion of the casing and in position to receive upward pressure from ice rising in the nipple whereby the piston is caused to rise in the casing by upward pressure of the ice, a resistance unit mounted on said piston, the casing and the piston being of electrically conductive material whereby regardless of the position of the piston in the casing mutually touching parts of the piston and the casing act together to form a conducting means for electricity, one end of the resistance unit being connected to the piston, means mounted on the piston for otherwise electrically insulating the resistance unit from the piston, a contact projecting from the top of the piston and connected to the other end of the resistance unit, a contact inside the casing carried thereby but insulated therefrom, a coil spring inside the casing above the piston for normally holding the piston in the lower portion of the casing, a contact device at the top of the casing, said contact device being normally separated by the said coil spring from the said projecting contact, said contacts being so spaced in the direction of rise of the piston that when the piston is forced upward against said spring by ice rising in said nipple said contacts engage to connect the resistance with a source of energy, the resistance unit in the piston being insulated from the latter by means including a body of ceramic material, said resistance unit being a circularly arranged coil of a resistance element, said body having a groove in its bottom in which said coil is seated.

4. An anti-freeze device for preventing the

freezing of water in a cooling system, comprising a casing, a nipple at its lower end opening into the lower portion of the casing, said nipple being connected to the cooling system, a piston normally resting on the lower portion of the casing and in position to receive upward pressure from ice rising in the nipple whereby the piston is caused to rise in the casing by upward pressure of the ice, a resistance unit mounted on said piston, the casing and the piston being of electrically conductive material whereby regardless of the position of the piston in the casing mutually touching parts of the piston and the casing act together to form a conducting means for electricity, one end of the resistance unit being connected to the piston, means mounted on the piston for otherwise electrically insulating the resistance unit from the piston, a contact projecting from the top of the piston and connected to the other end of the resistance unit, a contact inside the casing carried thereby but insulated therefrom, a coil spring inside the casing above the piston for normally holding the piston in the lower portion of the casing, a contact device at the top of the casing, said contact device being normally separated by the said coil spring from the said projecting contact, said contacts being so spaced in the direction of rise of the piston that when the piston is forced upward against said spring by ice rising in said nipple said contacts engage to connect the resistance with a source of electrical energy, said contact device including a spring pressed plunger rod adapted to be compressed by the rising piston and keep continuous electrical contact in order to close the electric circuit and keep the resistance unit heated, the resistance unit in the piston being insulated from the latter by means including a body of ceramic material, said resistance being a coiled length of a resistance element, said body having an annular groove in its bottom in which said coiled length is positioned, said body having an aperture extending upward from said groove to the top of the body and through which aperture is extended an end portion of said element, said end portion being connected to the piston.

5. An anti-freeze device for preventing the freezing of water in a cooling system, comprising a casing, a nipple at its lower end opening into the lower portion of the casing, said nipple being connected to the cooling system, a piston normally resting in the lower portion of the casing and in position to receive upward pressure from ice rising in the nipple whereby the piston is caused to rise in the casing by upward pressure of the ice, a resistance unit mounted on said piston, the casing and the piston being of electrically conductive material whereby regardless of the position of the piston in the casing mutually touching parts of the piston and the casing act together to form a conducting means for electricity, one end of the resistance unit being connected to the piston, means mounted on the piston for otherwise electrically insulating the resistance unit from the piston, a contact projecting from the top of the piston and connected to the other end of the resistance unit, a contact inside the casing carried thereby but insulated therefrom, a coil spring inside the casing above the piston for normally holding the piston in the lower portion of the casing, a contact device at the top of the casing, means mounted on the piston for otherwise electrically insulating the resistance unit from the piston, a contact projecting from the top of the piston and connected to the other end of the resistance unit, a contact inside the casing carried thereby but insulated therefrom, a coil spring inside the casing above the piston for normally holding the piston in the lower portion of the casing to disengage said contacts, said contacts being so spaced in the direction of rise of the piston that when the piston is forced upward against

said spring by ice rising in said nipple said contacts engage to connect the resistance with a source of electrical energy, the resistance unit in the piston being insulated from the latter by means including a body of ceramic material in the piston, said piston being comprised of an open topped cup and a disc cover, said resistance unit being a circularly arranged coil of a resistance element, said body having a groove in its bottom in which said coil is seated, said body having an aperture extending upward to the top of the body and through which aperture is passed an end extension of said element, said end extension being connected to said cover.

6. An anti-freeze device for preventing the freezing of water in a cooling system, comprising a casing, a nipple at its lower end opening into the lower portion of the casing, said nipple being connected to the cooling system, a cylinder normally resting in the lower portion of the casing and in position to receive upward pressure from ice rising in the nipple whereby the piston is caused to rise in the casing by upward pressure of the ice, a resistance unit mounted on said piston, the casing and the piston being of electrically conductive material whereby regardless of the position of the piston in the casing mutually touching parts of the piston and the casing act together to form a conducting means for electricity, one end of the resistance unit being connected to the piston, means mounted on the piston for otherwise insulating the resistance unit from the piston, a contact projecting from the top of the piston and connected to the other end of the resistance unit, a contact inside the casing carried thereby but insulated therefrom, a coil spring inside the casing above the piston for normally holding the piston in the lower portion of the casing, a contact device at the top of the casing, said contact device being normally separated by the said coil spring from the said projecting contact, said contacts being so spaced in the direction of rise of the piston that when the piston is forced upward against said spring by ice rising in said nipple said contacts engage to connect the resistance with a source of electrical energy, the resistance unit in the piston being insulated from the latter by means including an apertured body of mica in the bottom of the piston, and a ceramic body above said mica body, said ceramic body having a recess in its bottom for housing said resistance unit, said contact device including a spring pressed plunger rod adapted to be compressed by the rising piston and keep continuous electrical contact in order to close the electric circuit and keep the resistance unit heated, said plunger rod comprising a projecting plunger pin at one end and a retaining head at the other end, a compression spring contacting the retaining head at one end and a fixed electrical terminal at the other end, and a ground terminal attached to said casing.
